(57) **CLAIM**

The ornamental design for finger probe device, as shown and described.

DESCRIPTION

FIG. 1 is a front plan view of a finger probe device showing my design.

FIG. 2 is a back plan view thereof.

FIG. 3 is a top view thereof.

FIG. 4 is a bottom view thereof.

FIG. 5 is a left view thereof.

FIG. 6 is a right view thereof.

FIG. 7 is a first perspective view thereof; and,

FIG. 8 is a second perspective view thereof.

The broken lines are included for the purpose of illustrating portions of the finger probe device that form no part of the claimed design.

1 Claim, 6 Drawing Sheets
